UNITED STATES PATENT OFFICE.

ARTHUR O. AUSTIN, OF BARBERTON, OHIO, ASSIGNOR, BY MESNE ASSIGNMENTS, TO THE OHIO BRASS COMPANY, OF MANSFIELD, OHIO, A CORPORATION OF NEW JERSEY.

INSULATOR AND FITTING THEREFOR.

Application filed March 1, 1923. Serial No. 621,969.

This invention relates to insulators which are connected or supported by members which pass thru openings in the insulator proper, there usually being two or more 5 openings arranged at an angle to each other with interposed dielectric material so that the connectors are interlinked but separated by the material of the dielectric member.

In insulators of this type, it is desirable to 10 provide fittings which can be economically manufactured and quickly and easily connected and which will afford sufficient mechanical strength to withstand the stresses to which they are subjected.

15 The invention has for its object the provision of combined insulators and fittings which will meet the requirements outlined above, and which shall be of improved construction and operation.

20 The invention is exemplified in the combination and arrangement of parts shown in the accompanying drawings and described in the following specification, and it is more particularly pointed out in the appended 25 claims.

In the drawings, Figure 1 is an elevation showing one embodiment of the present invention, the connector having a portion broken away.

30 Figure 2 is a section on line 2—2 of Figure 1.

Figure 3 is an elevation of a connector plate.

Figure 4 is an edge view of the plate 35 shown in Figure 3.

Figure 5 is a view similar to Figure 2, showing the clamping member applied to a connector rod of a different cross section.

Figure 6 is an elevation of a modified 40 construction.

Figure 7 is a section on line 7—7 of Figure 6.

Figure 8 is an elevation of another modification.

45 Figure 9 is a section on line 9—9 of Figure 8.

Figure 10 shows a different form of nut lock that may be used in the combination.

Figure 11 is a section on line 11—11 of 50 Figure 10.

In the form of the invention shown in Figure 6, a connector for the links 13 is provided similar to that shown in Figure 5 but in which the tongues 16 project sufficiently

through the openings 17 to receive cotter pins 55 25 and provide against any chance of the tongues being drawn from the openings. As shown in this form the bolt may be provided with a squared opening in the plate 15 and a lock washer 26 to prevent loosening of the nut.

In Figures 8 and 9 the tongues 16 are bent outwardly at their ends after insertion as shown at 27 and a lock tongue 28 for the 60 nut is cut and bent outwardly from the clamping plate in position to be bent against a face of the nut when tightened up to prevent unscrewing.

In Figures 10 and 11 a different form of locking tongue for the nut is shown.

As illustrated in the drawings, the numeral 10 designates insulators of the general type in my prior Design Patent No. 56,262. These insulators are provided with perforations 11 and 12 arranged at right angles to 70 one another thru which connector links 13 are threaded. The links 13 have hooks 14 formed on the end thereof for engagements with holding clamps by means of which the 75 insulators are connected to one another.

It should be noted that the openings 11 and 12 are elongated in section in the direction of the length of the string, so as to permit the passage of the hooks 14 thru the openings. The clamping members for connecting the 80 ends of the links 13 comprise duplicate plates 15, which may be stamped from sheet metal or may be forgings or castings as the conditions require. Each plate is provided with a pair of tongues 16 bent at right angles to the 85 plane of the plate and with a pair of openings 17 for receiving the tongues 16 of the counter-part plate when the two are connected together. The tongues are positioned to enter the hooks 14 so that when the plates 90 15 are secured to one another by the bolt 18, the links 13 of adjacent insulators will be firmly connected.

It should be noted that each of the plates 15 is provided at one edge with a flange 19 100 which engages the outer legs of the hooks 14 and prevents straightening or unwinding of the hooks under the load of the insulator. The flanges 19 are reinforced by supplementary flanges 20 formed at the ends of the 105 tongues 21 on each of the plates 15. The sides of the plates 15 are provided with strengthening ribs 22 to add stiffness to the plates. The

Links 13 may be circular in cross section as shown in Figure 2, or they may have other cross sectional shapes. The cross sectional shape shown in Figure 5 is found to be desirable in some instances. As there shown, the face of the link 13 adjacent the insulator is rounded at 23. This shape conforms to the opening in the insulator with which the link contacts and thus gives a good bearing surface between the link and insulator. The opposite face of the link is flat as shown at 24, so that a relatively close bend can be formed for the hook 14, which will conform closely to the tongue 16 which the hook engages.

It will be noted that the various parts of the connection may be cheaply made by automatic machinery and that when completed, a strong connection is provided. The abutment members 19 and 20 add greatly to the strength of the connection since they overcome all danger of unbending the hooks 14. The plates 15 are exact duplicates so that only one style of plate need be furnished the workmen for installing the devices, thus avoiding danger of improper installation.

It should also be noted that bolt 18 cannot be secured in place until the holding plates are properly fitted to one another. After the parts are connected, the links 13 are held firmly in place in the grooves in the sides of the insulators so that the assembled parts may be handled without danger of displacement. A close coupling of the insulator is also provided, as the parts require no relative movement in the direction of the length of the string during the coupling operation.

I claim:

1. Means for connecting a pair of insulators comprising U shaped links arranged to extend through the respective insulators, the ends of said links being bent upon themselves to form hooks, a pair of clamping plates arranged to bridge the space between the ends of said links, each plate having a pair of projections thereon arranged to engage a hook of each of said links and having a pair of openings therein for receiving the projections of the complementary plate, a fastening

device for securing said plates in place on said links and abutment members on said plates to prevent straightening of said hooks under load.

2. In combination, a pair of insulators having longitudinally extended grooves and transverse openings therethru, said openings being elongated in section in the direction of the length of said grooves, U shaped connecting links threaded thru said openings and positioned in said grooves and having the ends thereof bent upon themselves to form hooks arranged in the plane of said links, a pair of duplicate clamping plates each having tongues thereon for entering said hooks and having openings for receiving the tongues of the complementary plate, a bolt for securing said plates in position on said hooks and bridging the space between said links and abutment members on said plates for engaging the free ends of said hooks to prevent unbending thereof under the load of said insulator.

3. A connector for an insulator comprising a supporting link adapted to extend through the interior of the insulator, connector hooks on the ends of said link having rigid, backwardly bent, free ends and a clamp for said hooks having tongues extending through the hooks and having abutments for engaging the free ends of the hooks to prevent outward bending thereof.

4. Means for connecting a pair of insulators comprising U shaped links arranged to extend through the respective insulators and clamps for connecting the ends of said links, said clamps comprising a pair of plates bridging the legs of said U shaped links, each plate having a pair of tongues projecting therefrom and engaging the ends of said links and also a pair of openings for receiving the tongues of the complementary plate and means for securing said plates together.

In testimony whereof I have signed my name to this specification on this 24th day of February, A. D. 1923.

ARTHUR O. AUSTIN.
